(57) **CLAIM**

The ornamental design for a tire, as shown and described.

DESCRIPTION

FIG. 1 is a front perspective view of a tire showing the claimed design;

FIG. 2 is a front view thereof;

FIG. 3 is a rear view thereof;

FIG. 4 is a top plan view thereof, the bottom plan view being the same;

FIG. 5 is a right side view thereof;

FIG. 6 is a left side view thereof;

FIG. 7 is an enlarged view taken along line 7-7 in FIG. 1;

FIG. 8 is an enlarged view of the portion 8-8 in FIG. 2;

FIG. 9 is a cross-sectional view taken along line 9-9 in FIG. 8;

FIG. 10 is a front perspective view of another embodiment of a tire showing the claimed design;

FIG. 11 is a front view thereof;

FIG. 12 is a rear view thereof;

FIG. 13 is a top plan view thereof, the bottom plan view being the same;

FIG. 14 is a right side view thereof;

FIG. 15 is a left side view thereof;

FIG. 16 is an enlarged view taken along line 16-16 in FIG. 10;

FIG. 17 is an enlarged view of the portion 17-17 in FIG. 11; and,

FIG. 18 is a cross-sectional view taken along line 18-18 in FIG. 17.

In the drawings, the broken lines show portions of the tire that form no part of the claimed design.

1 Claim, 18 Drawing Sheets
